FEED DEVICE FOR ROTARY BEATER MILLS WITH MEANS
FOR PREVENTING BLOW-BACK OF MATERIAL

Filed June 2, 1947

UNITED STATES PATENT OFFICE

2,530,313

FEED DEVICE FOR ROTARY BEATER MILLS
WITH MEANS FOR PREVENTING BLOW-
BACK OF MATERIALCarl D. Parten, Minneapolis, Minn., assignor to
Schutz-O'Neill Co., Minneapolis, Minn., a cor-
poration of Minnesota

Application June 2, 1947, Serial No. 751,846

1 Claim. (Cl. 241—186)

1

This invention relates to a device for grinding solids to a fine state of subdivision. More particularly, it relates to an improved mounting for the parts of the grinding machine and to improved means for supplying material to be ground to the grinding chamber.

In the grinding mills of the screen type as heretofore known, excessive vibration and wear of the parts has been a common experience. Another difficulty in such devices is found in the means for supplying material to be ground to the grinding chamber. The means for supplying material in the grinders heretofore known, particularly in hammer mills of the screen type, has been a simple hopper of decreasing cross-sectional area, which merely directs the material to be ground into the chamber. With hoppers of this type, there is considerable throwing back up into the hopper of material supplied to the grinding chamber unless the rate of feed of material to the grinding chamber is kept low, not to mention the other obvious disadvantages of such a structure.

An object is to provide a grinding machine such as a hammer mill pulverizer of the screen type having improved means for supplying material to be ground to the grinding chamber whereby the capacity of the mill is increased.

A further object is to provide a hammer mill pulverizer of the screen type including means for supplying material to be ground to the grinding chamber in which material thrown back from the grinding chamber is caught and returned to the grinding chamber without escaping into the atmosphere.

Other objects will appear hereinafter.

The means by which the foregoing objects have been accomplished are embodied in the illustrative devices shown in the accompanying drawings which form a part of this specification and in which:

Figure 1 is a view, partly in central vertical cross-section, of a pulverizer embodying features of the present invention;

Figure 2 is a vertical cross-sectional view on the line 2—2 in Figure 1;

Figures 3, 4, 5 and 6 are views similar to Figure 2 showing modified forms of feeding means.

As shown in Figure 1, the grinding machine generally designated 10 includes a base 12 having a passageway 14 extending longitudinally thereof between a grinding chamber 16 at one end and a blower chamber 18 at the other. Formed integrally with the base at each end thereof are vertically-extending walls 20 and 22 and associated

2

walls 24 and 26 extending at right angles thereto, which partly enclose the lower portion of the chambers 16 and 18. The walls 20 and 22 both terminate about midway of the chambers 16 and 18 respectively, and are provided at their upper edges with flanges 21 and 23. The upper portion of the chambers 16 and 18 is partially enclosed by a pair of semi-cylindrically housings 25 and 27, open on one end. These housings 25 and 27 are flanged as at 29 and 31 along their lower edges, and are secured in place by fastening means extending through the respective pairs of flanges 29—21 and 31—23. The closure of chambers 16 and 18 is completed by plates 28 and 30 respectively, which are bolted to flanges 32, 33, 34, and 35, formed respectively on housing 25, base 12, housing 27, and base 12.

A pair of bearings 36 and 38 are mounted on the base 12 between the walls 20 and 22. The shaft 40 is rotatably mounted on these bearings. At one end in the chamber 16 the shaft 40 has a set of three discs 42 fixed thereon. These discs carry hammers or beaters 44. On the other end of the shaft 40 in chamber 18 a set of blower blades 46 is fixed on shaft 40. Between the bearing members 36 and 38 the shaft 40 carries a driving pulley 48.

The balance obtained in this structure is readily apparent from the drawings. By having the driving pulley 48 mounted in the center of the shaft 40, the two driven members on either end and the bearings between the driving pulley and the respective driven members, as nearly a perfect balance as possible is obtained. The central location of the bearings also contributes to improved operation of this pulverizer, and the fan and beaters are readily accessible.

As indicated above, the pulverizer which forms the subject of this invention, in addition to the improved arrangement of the parts, is also provided with novel means for feeding material to be ground into the grinding chamber. In general, the feeding means shown in Figures 2 through 6 are characterized by the feature that they permit material supplied to the grinding chamber to be thrown back without permitting the material so thrown back to escape into the atmosphere.

In the embodiments of Figures 2 and 3, it will be seen that the material to be ground is fed into the grinding chamber in a generally radial direction, whereas in Figures 4, 5 and 6 the material to be ground is fed into the grinding chamber in a direction which is substantially tangential to the rotating grinding member.

Referring first to Figure 2, it is observed that material to be ground is admitted to the grinding chamber 16 through a circular opening 50 formed in the annular wall portion of the housing member 25 just above the flange 29. Material to be ground reaches this opening through a conduit 52, which includes a portion 54 extending generally radially outwardly from the housing 25, a portion 56 extending vertically upwardly from the portion 54, another portion 58 extending horizontally from the vertical portion 56, and finally, a portion 60 which extends upwardly at an angle of about 45° from the horizontal portion 58. The open end of the portion 54 is provided with a flange 62 which is secured to the housing 25 by any suitable means, such as welding. At the junction of the horizontal portion 58 and the vertical portion 56 a semi-circular baffle 64 is secured within the horizontal section 58 to completely block the upper half thereof. Material to be ground is first filled into the portion 60 of the conduit. Feed of material in the portion 60 is controlled by an adjustable feed gate 66 mounted in the portion 60. The gate 66 is slidably mounted in a slotted guide 68 secured to the conduit member 69 with its slot in alignment with a corresponding slot through conduit section 69. A set screw 70 mounted in the guide 68 permits the feed gate 66 to be secured in any desired position.

As indicated by the arrow 72 in Figure 2, the discs 42 in the embodiment of the invention shown in Figure 2 rotate in a clockwise direction when viewed from the end of the shaft 40 on which these discs are mounted. Material supplied through the conduit 52 thus enters the grinding chamber 16 at a place where the hammers 44 are moving upwardly. To aid the grinding action of the hammers 44, a corrugated section 74 which may be removable is secured to the inner surface of the annular wall portion 76 of the housing 25 between the opening 58 and the lower end of the wall portion 76 on the other side of chamber 16.

The maximum size of ground material leaving the grinding chamber 16 is determined by a screen 78 mounted in the lower portion of the chamber. The screen 78 is provided at its upper end with flanges 80 and 82 which are secured at either side of chamber 16 between flanges 29 and 21, which are suitably relieved at these points to accommodate the flanges 80 and 82. Between the vertical wall 20 and the end plate 28 a pair of side walls 84 and 86 extend inwardly and downwardly from the vertical walls 24 and join a bottom wall 88 of base 12, which is a continuation of the lower wall of the conduit 14. These walls complete the closure of the chamber 16. The lower portion of chamber 16 opens into the conduit 14 through an opening 90 formed in the vertical wall 20.

In the operation of a pulverizer embodying the features illustrated in Figure 2, material to be ground is filled into the conduit portion 60, the feed gate 66 is positioned to give the desired rate of feed, and the material to be ground passing beyond this gate proceeds through the horizontal conduit 58 past the baffle 64, downwardly through the vertical conduit 56, and then through the radially extending conduit 54, and enters the chamber 16 through the opening 50. The hammers 44 are moving in the direction indicated by the arrow 72, and they pick up the material entering chamber 16 and throw it against the corrugated section 74. In this manner the large pieces of solid material are disintegrated or pul-

verized, and as they are carried around by the rotating grinding member, they are eventually brought to the screen 78 through which a portion of the material which is fine enough passes. A fan such as the fan 46 pulls air through the conduit 14 from chamber 16, drawing with it the ground material passing the screen 78. The air carrying the ground material is discharged through the exhaust 92 of the fan 46 to suitable collection means. By reason of the construction of the conduit 52, it is possible to operate under conditions such that a considerable portion of the material supplied to the chamber 16 is blown back through the opening 50, as, for example, by rotating the hammers 44 at relatively high speed or by supplying material to be ground to the grinding chamber at a relatively high rate. The advantage of operating under conditions where a lot of material is blown back through the opening 50 is that maximum grinding capacity is obtained under these conditions, that is to say, the grinding capacity of a given unit increases within certain limits as the amount of material blown back through the opening 50 increases. In previously-known pulverizers it was not possible to operate with any substantial amount of blow-back through the opening into the grinding chamber because the material so blown back escaped to the atmosphere and was lost or else forced to be thrown into the atmosphere and lost, or both. These losses are prevented by the conduit 52. The velocity of material blown back through the opening 50 is spent by impact with the walls of the conduit portions 54 and 56 particularly. Material deflected by these walls is caught, at least in part, by the baffle 64. Any small amount which escapes past the baffle 64 spends itself against the feed gate 66 or is caught and carried back toward the chamber 16 by the material being supplied to the grinder through the conduit portion 60. This material moving through the portion 60 is under a head which is greater than the force of any materials escaping past baffle 64.

The embodiment shown in Figure 3 differs mainly in that the opening 92 in the annular wall 76 of housing member 25 is located in the top of the housing 25 instead of on one side, as is the opening 50. The conduit 94 includes a vertically-extending portion 96 which also extends radially and thus takes the place of portions 54 and 56 in the conduit 52. Vertically-extending portion 96 joins a horizontally-extending portion 98, which is in turn joined by portion 100 extending up at an acute angle. It will be seen that these latter two portions correspond respectively to the portions 58 and 60 of conduit 52. Material to be ground is supplied to the open end of the conduit 100, and the rate of feed thereof toward the chamber 16 is controlled by feed gate 102, which, like the feed gate 66, is mounted in a slotted guide 104, secured to the conduit 100 in line with an opening therethrough. Gate 102 is slidably in the guide 104 and may be secured in any desired position by the adjustment screw 106. The flange 108, formed on the open end of the conduit portion 96 is secured to the housing 25 by welding or other suitable means. A baffle 110, identical with the baffle 64, is secured inside the conduit at the junction of the vertical portion 96 and the horizontal portion 98.

The direction of rotation of the hammers 44 in the embodiment of Figure 3 is not material due to the central location of the opening 92. By way of illustration, the arrow 112 is included

to show that the hammers 44 can be rotated in a clockwise direction, as in the embodiment of Figure 2. A corrugated section 114, similar to the section 74, is secured to the annular wall 76. Due to the location of the inlet to the chamber 16, it is necessary to provide an opening 116 through the corrugated section 114, which is positioned in alignment with the opening 92.

The embodiment of Figure 3 is otherwise identical with that of Figure 2. It includes the same screen 78 having flanges 80 and 82, which are clamped between the flanges 29 and 21 to hold the screen in place. It also includes the walls 84, 86, and 88, completing the closure of the bottom of the chamber, and it includes the opening 90 through the wall 20. The operation of the embodiment of Figure 3 is also similar to that of Figure 2. Material to be ground, entering the chamber 16 radially through the openings 92 and 116, is engaged by the hammers 44 and driven against the corrugated section 114. Ground material eventually passes through the screen 78 and is carried by a current of air through the conduit 14 and discharged by a fan 43 through an exhaust 92 to suitable collection means.

The main advantage of the embodiment shown in Figure 3, as compared with other embodiments, is that it is relatively easy to construct. There is slightly less blow-back in this form under otherwise equivalent conditions. Material which is blown back through the openings 92 and 116 spends its force mainly against the walls of conduit section 96 and against the baffle 110. Any small amount of material which does pass the baffle 110 is caught by the gate 102 or the material moving past the gate in the manner already described above in connection with Figure 2.

The embodiment of Figure 4 gives the maximum single pass grind; that is, the maximum amount of grinding for a single passage of material through the pulverizer, and, accordingly, this embodiment provides the maximum capacity for a given size of machine. In Figure 4 the opening 118 in wall 76, through which material to be ground is supplied to the chamber 16, like the opening 50, is located just above the flange 29. It is of the proper size and shape to conform with the vertical portion 120 of the conduit 122, which directs the material to be ground into the grinding chamber 16, through the opening 118 in a direction which is tangential to the path of the movement of the hammers 44. Because this embodiment involves the maximum amount of blow-back through the opening into chamber 16, the horizontal conduit section 124 joins the vertical portion 120 intermediate its ends, thereby providing a surge chamber 126 in the upper part of the vertical conduit portion 120. The size of this surge chamber 126 is further increased by the baffle 128, located at the junction of the vertical conduit 120 and the horizontal section 124. As in the other embodiments, the horizontal section 124 in turn communicates with a portion 130 extending upwardly at an angle to the vertical. A flange 132, formed on the lower end of the vertical portion 120, is secured by riveting or welding or any other desired means to the housing 25 to hold the conduit 122 in place. A feed gate 134 is slidably mounted in a guide 136 secured to the conduit portion 138 in alignment with an opening therethrough. An adjustment screw 138 permits the gate 134 to be secured in any desired position.

Figure 4 also illustrates a feature of construction which can be included with any of the em-

bodiments shown in any of the other figures to provide better control of the head of pressure of the material to be ground, which is being supplied through the conduit portion 130. To this end, the portion 130, into which the material to be ground is supplied, instead of being rigidly connected to the horizontal conduit section 124, is pivoted thereto at 140 at the uppermost point of the junction of the two sections and over the remainder of its circumference is slidably extended within the horizontal portion 124, which, for this purpose, is extended outwardly and curved upwardly, as indicated at 142. In this way, the section 130 can be adjusted to various angles with the vertical, at all of which there is a tight joint between sections 124 and 130. It is apparent, of course, that with a given amount of material in the conduit 130, the head of pressure at feed gate 134 depends upon the angle 130 extends.

The embodiment of Figure 4 is particularly characterized by the feature that the material to be ground is supplied to the chamber 16 tangentially in a direction opposite that in which the hammers 44 are moving adjacent the inlet 118. The direction of rotation of the hammers 44 is, accordingly, as indicated by the arrow 144. Between the inlet 118 and the opposite side of the housing 20, a corrugated section 146 is secured to the wall 76 to cooperate with hammers 44, as in the other embodiments described above. The lower half of the grinder structure is identical with that in the other embodiments and has already been described above.

The operation of the structure illustrated in Figure 4 is as follows: The conduit section 130 is set at the appropriate angle to provide the desired head at the feed gate 134. Material supplied to the conduit section 130 moves past the feed gate 134 through the section 124 and thence downwardly to chamber 16. After it is ground, the material passes, as in the other embodiments, through screen 78 and is eventually carried to a collection means by a current of air. It has already been pointed out above that this particular form gives maximum feed-back through the opening 118, and, accordingly, additional provision is made in the conduit 122 to spend the force of the material fed back and prevent it from escaping to the atmosphere. It is a particular advantage of this embodiment that the material being ground can be caused to feed back the larger particles until they are broken up sufficiently so that they no longer have weight enough to oppose the head of pressure of the fresh material coming in to be ground. In this manner, a sort of automatic separation and regrinding of the larger particles is obtained.

In contrast to the embodiment of Figure 4, that of Figure 5 provides a minimum of feed-back. The opening 148 in the wall 76, through which material to be ground enters chamber 16, is located near the top of the housing 25. Because of the low feed-back, the conduit 150, through which material to be ground is brought to the opening 148, is relatively simple in structure. As may be seen, it includes a portion 152 extending generally tangentially with respect to the path of travel of the hammers 44 adjacent the opening 148. The portion 152 joins a second portion 154, extending generally vertically. This portion 154 is shown as somewhat enlarged in cross-sectional area over the portion 152. In any of the embodiments shown, the portion of

the conduit into which the material to be ground is first supplied may, if desired, be considerably enlarged over the remainder of the conduit and may include a hopper, if desired. To provide means for securing the conduit 150 to the housing 25, the open end of section 152 is provided with a flange 156, which is welded or otherwise fastened to housing 25 about the opening 148. The conduit section 152 is provided with a feed gate structure which, like the others previously described, includes a gate 158, a guide 160, and an adjustment screw 162. In this embodiment, in which the hammers rotate in the direction indicated by the arrow 164, blow-back is largely or completely prevented by providing a baffle 166. The baffle 166 is shaped to close off the upper portion of the conduit section 152 when it extends generally radially with respect to the discs 42. As in the other embodiments, a corrugated section 168 is secured to the wall 76 of housing 25. An opening 170 is provided in the corrugated section 168 in alignment with opening 148. The lower half of the grinding chamber structure, which is the same as that in the other embodiments, has already been described.

The embodiment of Figure 5 operates with a minimum of blow-back since the material to be ground, moving past the gate 158, enters the chamber 16 in a direction tangential to the path of movement of the hammers 44, and at its point of entry is moving in the same direction as the hammers. Actually, in this form the rotating hammers tend to pull material into the chamber rather than to blow it back, as in the structure of Figure 4. Any small amount of material which may tend to blow-back is caught by the baffle 166 and returned to chamber 16. Thus, in Figure 5, the blow-back problem is solved mainly by minimizing the amount of material which leaves chamber 16, rather than by providing a circuitous conduit in which the force of the material blown back may be spent against the walls.

In the structure shown in Figure 6, the conduit 172 extends into the chamber 16 which is enlarged by replacing the curved wall 76 of housing 25 on one side with a vertical wall 174. The hammers move in the direction indicated by the arrow 173 and the wall of conduit 172 thus serves as a baffle. Material being ground is thrown up into the space between the lower part of the wall of conduit 172 and the vertical wall 174 and then falls back into the periphery of the mill again.

Plate 28 and wall 25 are extended out to the wall 174 to complete the closure of chamber 16. Conduit 172 extends into chamber 16 at about the same angle as conduit 150 through an opening 176. This conduit is generally the same in structure as conduit 150 and only the lower portion which differs is shown. A corrugated section 180 similar in structure and mounting to those previously described is provided to aid in the pulverizing. The lower half of the grinding chamber is not shown since it is the same as that in the other embodiments. In addition to the differences noted, it is further pointed out that conduit 172 does not have a flange such as 156, and instead is secured to housing 25 and plate 28 by welding as at 178 around the opening 176. In the embodiment of Figure 6 as in that of Figure 5, the feed back is low because the feed is tangential in the direction of movement of the hammers which tend to pull the feed into the chamber 16 and thus the conduit 172 gives sufficient baffling effect.

This invention is not intended to be limited to any particular form of rotating elements in the grinder structure. Instead of the hammers 44 carried by discs 42, swinging hammers or other equivalent grinding means may be employed within the scope of the invention. It will also be understood that the invention is not intended to be limited to a structure in which the base has a passageway such as the passageway 14, through which ground material is drawn off.

The advantages of this invention will be apparent from the foregoing description. By locating the driving member in a central position with the grinder on one end, and the fan blade on the other end of the main shaft, a well-balanced structure is obtained. The balance of the structure is also aided by the location of the two bearings between the driving pulley 48 and the fan and grinder respectively. Such a balanced structure has the advantage of decreasing vibration and at the same time decreasing wear of the parts.

The various forms of conduit for supplying material to be ground to the grinding chamber, as illustrated in Figures 2 to 6, solve the problem of blow-back and thereby increase the capacity of the grinder. Whether the blow-back is minimized by admitting material tangentially, as in Figures 5 and 6, or is controlled as in the other embodiments, the capacity of the grinder is increased as compared with the conventional grinding machine, in which material to be ground is supplied to the grinding chamber through a simple hopper structure. It will be apparent that the pulverizer disclosed herein is suitable for pulverizing a wide variety of materials, such as, for example sugar and many other like materials.

It is apparent that many widely different embodiments of this invention may be made without departing from the spirit and scope thereof, and, therefore, it is not intended to be limited except as indicated in the appended claim.

I claim:

A grinding mill comprising a housing including a cylindrical top portion and providing an internal grinding chamber, a rotating hammer in said chamber, an inlet opening in the top portion of said housing positioned in advance of the vertical center line through the chamber and close to the rotating hammer with relatively small clearance therebetween and through which material to be ground is supplied, an outlet for ground material, and means for supplying the material to be ground to said inlet opening and including a closed conduit having a relatively short downwardly inclined conduit portion with one end in communication with said inlet opening and extending substantially tangentially with respect to the path of movement of said hammer across the inlet opening and positioned so that material moving from said conduit into the grinding chamber is travelling in substantially the same direction as the rotating hammer, an upstanding conduit portion in communication with the opposite end of said inclined conduit portion and providing an abrupt change of direction for material being fed therethrough, an adjustable feed gate positioned in the downwardly inclined conduit portion for controlling the flow of material therethrough, and a baffle depending from the upper wall of the said downwardly inclined conduit portion and disposed between said feed gate and said inlet opening, said baffle being inclined in the direction of feed of the material through the inclined conduit portion and termi-

nating substantially vertically above and adjacent the lower edge of said inlet opening whereby to close off the upper part of the inclined conduit portion and to trap blown-back material between the upper inclined edge of the baffle and the adjacent wall surface of the inclined conduit portion above the inlet opening.
